ATTORNEY

UNITED STATES PATENT OFFICE.

FRED C. MENDECK, OF HASKELL, TEXAS.

TICKET-DISTRIBUTER.

1,275,717.

Specification of Letters Patent. Patented Aug. 13, 1918.

Application filed January 18, 1917. Serial No. 143,117.

To all whom it may concern:

Be it known that I, FRED C. MENDECK, a citizen of the United States, residing at Haskell, in the county of Haskell and State of Texas, have invented certain new and useful Improvements in Ticket-Distributers, of which the following is a specification.

This invention relates to ticket distributors, and more particularly to a distributing case or file for assorting or distributing tickets in telephone offices and similar establishments for the purpose of assisting the accountant in keeping track of the various calls made and charges.

One of the main objects of the invention is to provide a distributor of the character stated of simple construction and operation which may be produced at very small cost. A further object is to provide a distributor having a plurality of compartments adapted to receive slips or tickets upon which the various charges are entered so as to permit the same to be filed in consecutive order in such condition as to enable entries to be made quickly and easily in the account books.

A still further object is to provide a distributor having visible and variable indexing means so arranged as to render it possible to provide a number or letter, or other suitable designation, for each compartment of the distributor so that the various account tickets or slips may be filed or placed in the distributor in chronological, alphabetical, or any other desired order. Further objects will appear from the detail description.

In the drawings:—

Figure 1 is a top plan view of a distributor constructed in accordance with my invention,

Fig. 2 is a detail top plan view of the indicating roll or cylinder,

Fig. 3 is a fragmentary front view of the distributor, and,

Fig. 4 is a transverse sectional view taken substantially on line 4—4 of Fig. 1.

The distributor comprises broadly, a rectangular body having a supporting casing at the upper edge of its back wall provided with a longitudinally extending slot, and an indicator roller or cylinder mounted in this casing for rotary adjustment and provided on its surface with indicating characters so spaced, and of such size, as to register with the compartments of the distributor and be visible through the slot of the casing. The

numeral 1 designates the bottom of the body of the casing which is provided with the back wall 2 disposed at right angles thereto. The metal is bent at the upper edge of wall 2 to provide a cylindrical casing 3 which extends the full length of body 1, one end of the casing extending somewhat beyond the end wall 4, as at 3^a. Casing 3 is provided, through its inner face, with a longitudinally extending slot 5 which extends the full length of the casing.

A plurality of sheet metal partition members 6 are secured in the body 1 of the distributor, these members serving to provide a series of compartments 6^a adapted to receive the usual slips or tickets upon which are marked the calls made or received at the particular telephone office in which the device is used, and the charge for such calls. By providing a suitable indicator for designating each compartment 6^a to correspond with a day of the month, a week day, or a letter of the alphabet, or the like, the various slips or tickets may be filed in the indicator according to the date or day on which the call marked on the ticket is received. By this means the tickets, as the various calls are received, are filed away and assorted so that these charges may be quickly and easily entered in the account books. By this means, the delay incident to assorting these slips or tickets when placed together on a desk file, or the like, as is now the common practice, is avoided.

An indicating roller or cylinder 7 is rotatably mounted in casing 3. This roller is provided, at one end, with a central stub 8. This stub is adapted to fit snugly through an aperture in an inclined brace and end plate 9 which is secured to the end plate 4^a of the distributor and extends across one end of casing 3. The other end of casing 3 is closed by a cap 10 which is secured to the shaft 11 at the other end of cylinder 7. By this means, when the cylinder is in position within the casing 3, both ends of the casing are closed and the cylinder may be quickly and easily removed from the casing if desired.

The surface of cylinder 7 is provided with a plurality of series of indicating characters. One of these series is indicated by A, and consists of spaced numbers from 1 to 31, a second series B consists of the months of the year, a third series C consists of the abbreviations for the days of the week, and a fourth series D consists of the letters of the

alphabet. In each of these series, the characters are so spaced as to correspond to the spacing of the compartments 6^a; and these characters are of somewhat less height than the width of slot 5 of casing 3. By this means, by rotating the cylinder 7, any desired series of characters may be exposed through slot 5, these characters serving as an index or mark for some or all of the compartments of the distributor.

For the purpose of rotating cylinder 7, a knurled finger knob 12 is secured on the outer end of shaft 11. This knob is provided with a reduced neck 13. A leaf spring 14 is secured at its inner end to the top of casing 3. A block 15 is secured on the outer end of the spring and is adapted to engage about the upper portion of reduced neck 13 of knob 12. The spring 14 acts to force block 15 into close frictional engagement with the neck of the knob, thus securing the cylinder 7 in rotary adjustment. In addition, this block engages between the knob 12 and the annular shoulder 13^a at the inner end of neck 13, thus securing the cylinder against axial movement. When it is desired to remove the cylinder from casing 3 this may be easily accomplished by raising spring 14 so as to disengage the block 15 from the thumb knob.

It will be obvious that, if desired, any desired series of characters may be used in place of the ones shown. Also, it will be equally evident, that by rotating cylinder 7 so as to bring the series A of the indicating characters opposite the slot 5 of casing 3 the compartments 6^a of the distributor will be numbered consecutively to correspond to the days of the month. By securing the cylinder in rotary adjustment so as to bring any of the other series of the indicating characters opposite the slot 5 some of the compartments 6^a will be marked to correspond with the months of the year, days of the week, or letters of the alphabet. It will be evident that there may be slight changes in the construction and arrangement of the various parts of my invention without departing from the field and scope of the same, and I

desire to include all such changes, as fall within the scope of the appended claims, in this application in which a preferred form only of my invention is disclosed.

What I claim is:—

1. A ticket distributor having a rectangular body formed from a continuous piece of material and provided with a cylindrical casing at the upper edge of the back wall of said body and extending the full length thereof and having a longitudinally extending slot, a plurality of spaced partition members secured in said body and forming a series of ticket receiving compartments, an indicating cylinder mounted in said casing and provided with a series of indicating characters adapted to be brought into register with said compartments, and means carried by the casing and engaging with said cylinder for securing the cylinder in rotary adjustment and normally preventing axial movement of the same in either direction.

2. A ticket distributor having a rectangular body formed from a continuous piece of sheet material, the upper edge portion of the back of said body being turned downward and inward to provide a cylindrical casing at the upper edge of the back and extending the full length of the body, said casing having a slot extending the full length thereof and positioned in the front of the casing, a plurality of spaced partition members secured in said body and forming a series of ticket receiving compartments, an indicating cylinder mounted in said casing for rotary adjustment and provided with a series of indicating characters of such size as to be visible through said slot and so spaced as to be brought into register with the ticket compartments when the cylinder is rotated, and means for securing said cylinder in rotary adjustment.

In testimony whereof I affix my signature in presence of two witnesses.

FRED C. MENDECK.
